UNITED STATES PATENT OFFICE.

JOSEPH C. GOODMAN, OF COLUMBUS, OHIO.

CAR-VENTILATOR.

1,358,198.

Specification of Letters Patent. Patented Nov. 9, 1920.

Application filed March 17, 1920. Serial No. 366,559.

To all whom it may concern:

Be it known that I, JOSEPH C. GOODMAN, a citizen of the United States of America, residing at Columbus, in the county of

5 Franklin and State of Ohio, have invented certain new and useful Improvements in Car-Ventilators, of which the following is a specification.

My present invention relates generally to 10 ventilators and more particularly to adjustable ventilators, my object being the provision of a ventilator particularly adaptable for railway cars, and one in which the unit structure may be duplicated practically 15 without limits to suit the needs.

With this in mind my invention resides in the ventilator to be now described with respect to the accompanying drawing, which forms a part of this specification and in 20 which,

Figure 1 is a front elevation,

Fig. 2 is a horizontal section therethrough,

Fig. 3 is a rear elevation,

25 Fig. 4 is a vertical cross section taken on line 4—4 of Fig. 2.

Figs. 5 and 6 are horizontal sections showing the rear adjustable closure in different positions.

30 Figs. 7 and 8 are respectively a partial front elevation and a vertical section through a slightly modified form,

Fig. 9 is a front elevation showing an extended form of the unit construction of Fig. 1, and

35 Fig. 10 is a diagram illustrating the application of the ventilator to a car.

Referring now to these figures and particularly to Figs. 1 to 6 inclusive my invention proposes a ventilator which includes a 40 rectangular casing 10 having top, bottom and side walls, which is open at its rear and is provided at its front with a wall 11 extending only partly thereacross from one of the side walls 12. Adjacent to the front 45 is an air controlling member consisting of a plate 13 having a reverting flange 14 and a rounded portion 15 connecting the plate and flange and forming in the angle between the same a pocket. The plate 13 is mounted be-

50 tween the top and base of the casing 10 with its rounded portion 15 adjacent to one side wall 12 and with its free edge and the free edge of its flange 14 overlapping the free edge of the partial front wall 11 and disposed in spaced relation thereto and respectively within and beyond the same. The

rounded portion 15 partially extends beyond the front of the casing so that cinders, dust and the like checked by virtue of the tortuous path it is thus necessary for the air to 60 take through the ventilator, may drop below the same.

At its rear portion the top and base of the casing have longitudinal guideways 16 in which an adjustable closure is slidably 65 mounted, this closure consisting of plates 17 and 18 having handles 19 and thus shiftable together toward either end of the casing for controlling the passage of air in the open position as will be seen by a comparison 70 of Figs. 2 and 5, as well as independently shiftable toward the relatively opposite ends of the casing to the closed position as seen in Fig. 6, it being obvious that the air is caused to traverse a more tortuous path with the 75 parts in the position of Fig. 5 than it is with the parts in the position of Fig. 2.

In either instance air passing inwardly between the flange 14 and the partial front wall 11 of the casing, is checked before it 80 continues inwardly between the said wall and the plate 13, to enable the pocket formed by the rounded portion 15 of the controlling member to catch cinders, dirt, dust and the like and in this way separate the same from 85 the air stream.

The construction as thus outlined constitutes a unit and various numbers of these units may be employed depending upon the requirements. In Fig. 9 I have shown a 90 series of three controlling members at 20 operatively included to control the passage of air through separate compartments of a casing 21, in each of the compartments of which the respective member is disposed in 95 relation to the other parts as described in connection with Figs. 1 to 6 inclusive.

In Figs. 7 and 8 I have shown horizontally extending air controlling members 22 in a casing 23, located to control the passage of 100 air through a series of compartments at the rear portions of each of which is a vertically movable sliding closure 24 of the construction previously described.

In Fig. 10 I have shown diagrammatically 105 the use of my invention in reversed relation at relatively opposite ends of a car 25, the ventilators at each end being turned so as to take in air at the front end of the car with respect to its direction of movement, when 110 proceeding in either direction, the oppositely turned rear ventilator operating to exhaust

air from the car under the influence of currents of air proceeding along the car side. In this way it is obvious that when moving in either direction the ventilator permits air to be taken in the front of the car and exhausted by a vacuum at the rear of the car.

With either of the forms of the invention shown and described it is furthermore obvious air will be taken into the car at its front and expelled therefrom at its rear so that effective and efficient ventilation is secured. As shown in the diagram the form of the multiple ventilator of Fig. 9 may be utilized but it is equally obvious that the ventilator of Figs. 1 to 6 inclusive may be used or a greater degree of multiplication resorted to, depending upon conditions of use and the requirements.

I claim:

1. A ventilator comprising a casing open at one side and having its wall at its opposite side partially cut away, an adjustable closure at the open side, and a member at the opposite side having portions overlapping the free edge of its wall in spaced relation upon relatively opposite sides thereof.

2. A ventilator comprising a casing open at one side and having its wall at the opposite side partially cut away, an adjustable closure at the open side, and a member at the opposite side having angularly projecting portions between which the free edge of said wall extends.

3. A ventilator comprising a casing having side walls and having a front wall extending partially across the front thereof from one of the side walls, and a member abutting the other side wall, having angularly projecting portions between which the free edge of the front wall extends, and also having a rounded portion forming a pocket opposite the free edge of the front wall as described.

4. A ventilator comprising a casing hav-

ing a front wall extending partially there- 45 across, a member having a dirt and dust receiving pocket extending partially at the front of the casing and having angularly extending portions between which the free edge of the said front wall extends as de- 50 scribed.

5. A ventilator comprising a casing having a front wall extending partially there- 45 across, a member having a dirt and dust receiving pocket extending partially at the front of the casing and having angularly extending portions between which the free edge of the said front wall extends, and a two-part sliding closure at the rear of the casing, as and for the purpose described. 60

6. A ventilator comprising a casing having a front wall extending partially there- 45 across, a member having a dirt and dust receiving pocket extending partially at the front of the casing and having angularly 65 extending portions between which the free edge of the said front wall extends, and a sectional closure at the rear of the casing whose sections are provided with handles and are simultaneously and independently 70 movable toward relatively opposite ends of the casing as described.

7. A ventilator comprising a casing having side walls and a front wall extending partially across the front from one of said 75 side walls, a member disposed vertically within the said casing and having angular portions, one within the casing and one outwardly beyond the casing, and between which angular portions the free edge of 80 the said front wall extends, said casing having guideways at its rear portion, and simultaneously and independently shiftable adjusting and closing slides mounted in the 85 said guideway as described.

In testimony whereof I have affixed my signature.

JOSEPH C. GOODMAN.
